UNITED STATES PATENT OFFICE.

THOMAS H. FARRELL, OF NEW YORK, N. Y.

BURGLAR-ALARM.

1,109,329.

Specification of Letters Patent. Patented Sept. 1, 1914.

Application filed March 11, 1912. Serial No. 682,937.

To all whom it may concern:

Be it known that I, THOMAS H. FARRELL, a citizen of the United States, residing at New York, county of New York, State of New York, have invented new and useful 5 Improvements in Burglar-Alarms, of which the following is a specification.

This invention relates to a burglar alarm which is inexpensive and can be readily attached to a movable object, to give audible 10 signal by setting a clock movement in motion, when a door or window is opened. The alarm rings a predetermined time and is automatically stopped by a detent 15 cooperating with a disk arranged in the train of the clock movement. The detent normally prevents movement of the clock mechanism by being in engagement with the disk, but when the door or window is opened, or 20 moved the detent is oscillated to unlock the disk, and consequently allow actuation of the clock movement and the hammer strikes an alarm. After each rotation of the disk the detent automatically engages a notch 25 in the disk and stops the rotation thereof and operation of the clock movement.

The novel features of the invention are more fully described in the following specification and claims and illustrated in the 30 accompanying drawing in which:

Figure 1 represents a front elevation partly in section showing the burglar alarm secured to a door. Fig. 2 is a section taken along the line $\alpha\alpha$ of Fig. 1. Fig. 3 is a perspective detail view of a disk and detent.

In this drawing the latter a designates a door and b a jamb. On the inner portion of the door is secured a case c to the interior of which is fastened the movement plates d . 40 Between these plates is mounted the clock mechanism consisting of a hammer e , escapement f and a coiled spring g having one end fastened to the arbor h and the other end to a post secured to the movement plates. To the arbor h is fastened the disk i having a notch j with a lip k formed by bending one of the side portions of the notch. A detent m is pivoted at n to the casing. One end of this detent normally 45 engages the notch while the other end is in contact with the tongue o of a latch. The latch is fastened to the jamb of the door and the tongue thereof can be retracted, when it is desired to open the door without 50 setting off the alarm. A spring p tends to hold the detent into the notch and forces

the other end of the detent against a stop formed in the casing. A cover q is mounted on the outer portion of one of the movement plates. A thumb nut r is inserted on top of the threaded part of the arbor and serves as a key for winding the spring. When it is desired to wind the spring the thumb nut is manipulated to rotate the disk and the lip k strikes on to the detent, thus 60 lifting the end of the detent out of the notch and allowing the disk to rotate. When the door is opened one end of the detent strikes on to the tongue o of the latch thus oscillating the detent to disengage it 65 from the notch j in the disk, the spring then 70 actuates the disk with the clock movement, and the hammer e strikes on to the inner wall of the metallic cover q thus ringing an alarm.

It will be seen that the disk revolves until the notch reaches the detent, which automatically moves into engagement with the notch to lock the disk and stop the movement of the clock mechanism.

I claim:

1. In a burglar alarm, the combination with a movable and a stationary object, of a normally wound spring motor mounted on the movable object, a disk provided with a notch and adapted to be rotated by said motor, and means normally engaging said notch and said stationary member, said means being governed by the winding up of the spring, or actuation of the movable object to release said disk to permit the operation of said motor, said means automatically reengaging said notch after each rotation of said disk to interrupt the operation of said motor.

2. In a burglar alarm, the combination with a movable and a stationary object, of a motor including an arbor with a normally wound coiled spring mounted on the movable object, a disk provided with a notch and secured to said arbor, and means normally engaging said notch and said stationary object, said means being governed by the winding up of the spring or actuation of the movable object to release said disk to permit the operation of said motor, said means automatically reengaging said notch after each rotation of said disk to interrupt the operation of said motor.

3. A burglar alarm comprising a motor including an arbor with a spring, a disk mounted on the arbor and operated by the

spring, a notch located in the circumference of the disk with a lip formed on one side of the notch, a detent to normally engage the notch and prevent movement of the disk, said lip being adapted to lift the detent out of engagement with the notch when the spring is being wound.

4. In a burglar alarm, the combination of a movable and a stationary object, of a normally wound spring motor, mounted on said movable object, means normally retaining said motor against operation, a disk provided with a notch and adapted to be engaged by said means, means carried by said disk adapted to actuate said first men-

tioned means to release said motor for winding, and means secured to said stationary object adapted to release said first-mentioned means upon actuation of said movable object, said first-mentioned means being adapted to automatically reengage said notch to interrupt the operation of said motor.

In testimony whereof I have hereunto set my hand in the presence of two subscribing witnesses.

THOMAS H. FARRELL.
